(57) **CLAIM**

The ornamental design for a monitor sheath, as shown and described.

DESCRIPTION

FIG. 1 is a perspective view of a monitor sheath showing a first embodiment of the claimed design;

FIG. 2 is a front view of a monitor sheath showing a first embodiment of the claimed design;

FIG. 3 is a rear view of a monitor sheath showing a first embodiment of the claimed design;

FIG. 4 is a lengthwise side view of the left side of a monitor sheath showing a first embodiment of the claimed design;

FIG. 5 is a lengthwise side view of the right side of a monitor sheath showing a first embodiment of the claimed design;

FIG. 6 is a widthwise side view of the bottom side of a monitor sheath showing a first embodiment of the claimed design;

FIG. 7 is a widthwise side view of the top side of a monitor sheath showing a first embodiment of the claimed design;

FIG. 8 is an expanded view of a portion of the lengthwise side view of the right side of a monitor sheath showing a first design as designated in FIG. 5; and,

FIG. 9 is an exploded view of the components of a monitor sheath showing a first embodiment of the claimed design. The broken away symbols indicate the appearance of any portion of the article between the break lines forms no part of the claimed design.

1 Claim, 5 Drawing Sheets
